UNITED STATES PATENT OFFICE.

JAMES TREGURTHA, OF MALDEN, ASSIGNOR, BY MESNE ASSIGNMENTS, TO
THE ADJUSTABLE TELEPHONE SUPPORT COMPANY, OF BOSTON, MASS.

SUPPORT FOR TELEPHONES.

SPECIFICATION forming part of Letters Patent No. 289,180, dated November 27, 1882.

Application filed April 6, 1883. (No model.)

To all whom it may concern:

Be it known that I, JAMES TREGURTHA, of Malden, in the county of Middlesex and State of Massachusetts, have invented certain new and useful Improvements in Supports or Stands for Telephonic and other Instruments, of which the following is a full, clear, and exact description.

This invention relates to a bracket more particularly designed for carrying telephonic instruments—transmitters and receivers, either or both—although it is also applicable to microscopic and other instruments.

The object of this invention is to provide a bracket for carrying such instruments which shall be capable of ready and easy adjustment, and thereby, with a suitable attachment or connection between the instruments and the bracket, enable the instruments to be most readily and easily adjusted in position for convenient use of either or both by operators.

This improved bracket, in substance, is composed of two arms, which are jointed at one end of each, so that they can be placed in line with or at an angle to each other, and are jointed at the other end of each, the one arm to a plate or other part suitable to be attached to the side wall of a room or other fixture, and the other arm to a standard or post, to which the telephonic or other instruments to be carried by said bracket are to be connected in any suitable manner, all substantially as hereinafter described, reference being had to the accompanying plate of drawings, in which this improved bracket is shown—

Figure 1 being a perspective view with some parts broken out and in section; Fig. 2, a plan view; Fig. 3, a side elevation with some parts in vertical section; and Fig. 4 is a detail view 40 of a modification, to be hereinafter described.

In the drawings, A represents a plate adapted to be fastened by screws or other suitable fastening devices to the wall B of a room or other suitable fixture.

C is a flat post or stud attached to and projecting at right angles horizontally from the plate A when said plate is fixed to the wall B. To this post C one end of an open tubular arm, D, is doubly jointed, as at E, and this arm D at its other end is jointed, as at F, to

one end of another open tubular arm, G, which in turn at its other end is doubly jointed, as at H, to a vertical post or rod-standard, O, carrying at either end thereof a telephonic instrument, such as a receiver, K, and a transmitter, L, which are connected to said rod by arms V and joints R S T U, substantially the same as described and shown in the specification and drawings in another application for Letters Patent of the United States made 55 by me, and filed on March 26, 1883; and as such connection of the instruments with said rod O, lettered the same in said application, forms of itself no part of the present invention, but is shown and referred to only as one 60 and a desirable way of connection for the instruments with said rod-standard, it is not deemed necessary to herein more particularly describe it.

The double jointing at E of the tubular arm D to the plate-post C, and at H of the tubular arm G to the rod O, carrying the telephonic instruments, is by means of joints M and M² and N and N², respectively. In each instance each joint M M² and N N² is composed of three 75 separate lifts or leaves, a c, of a circular-disk shape, and severally placed by their flat surfaces upon each other, with a washer, d, (see Fig. 3,) of leather or other suitable packing material, between them, and all secured together by a headed screw-bolt, f, passing concentrically through their several thicknesses and screwing into either of the outer lifts or leaves, a c, but loosely through the middle lift, b, which is thus made capable, if not 80 bound to the lifts at each side thereof by sufficiently screwing up of the axial screw-bolt, of being turned or rotated upon said axial bolt. The outer lifts or leaves, a c, of each of the joints are locked together by a pin, g, fastened 85 to one and entering loosely into a socket, h, of the other, and located in a lug, J, of one outer disk, and in an arm, hereinafter referred to, of the other outer disk. The said lugs and arms project from the edge and one side of 90 the lifts, and as a consequence, with either of said outer lifts fastened or held against turning in any manner, the other one thereof will be correspondingly held against movement; but if neither thereof is so fastened, 95 100

and otherwise they are free to be turned—that is, if not bound against the sides of the middle lift, *b*, by means of the center or axial bolt, *f*, or either of them held in any other way—then they, with said axial bolt, can be rotated, turning by said bolt within the center opening, and by the inner faces of each outer lift against the opposite faces of the middle lift. In the case of the joint *M* at the 10 wall-plate *A* the middle lift, *b*, is the stud or post *C* of said plate *A*, and the upper outer lift, *a*, of said joint *M* connects by an arm, *l*, to the middle lift, *b*, of the joint *M'*, which joint *M'* is at right angles to the joint *M* upon 15 the wall-plate *A*. The joint *M'*, by one outer lift, *a*, is connected by an arm, *m*, in extension of the tubular arm *D*, to one end of said tubular arm *D*, and this tubular arm by an extension, *n*, at its other end is connected to the outer lift, *c*, of the three lifts *a*, *b*, and *c*, which make the joint *F* between the two tubular arms *D* *G*, and said joint is the same in construction and arrangement of parts as previously described for the other 20 joints, *M* *M'* *N* *N'*. The middle lift, *b*, of the joint *F* is connected by an arm, *q*, in extension of the tubular arm *G*, to one end of said tubular arm *G*, and this tubular arm has an extension, *r*, at its other end, and is connected 25 by said arm or extension *r* to the middle lift, *b*, of the joint *N*, connected by one of its outer lifts, *a*, to the middle lift, *b*, of the joint *N'*, connected by an arm of one of its outer lifts, *a*, to the horizontal projecting tubular arm 30 *W* of the rod or standard *O*, to which the receiver and the transmitter are connected. The joints *N* and *N'* are at right angles to each other, as before stated, for the joints *M* and *M'* between the wall-plate *A* and tubular 35 arm *D*, and as a consequence the planes of rotation of the two joints of each set of double joints are at right angles to each other. The axial bolt *f* of the joint *M* at wall-plate *A* is made tubular, for the passage of the electric wires through it, and thence through the 40 tubular arm *D*, to and through the tubular arm *G*, to and through the tubular arm *W* of rod-standard *O*, to the transmitter and receiver.

50 The arms *D* *G*—preferably tubular, and jointed at one end to each other, and at the other end of each doubly jointed, the one, *D*, to a wall-plate, *A*, or equivalent part, and the other, *G*, to a rod-standard, *O*, or equivalent part, to which the telephonic or other instruments 55 are connected—constitute in substance the present improved bracket; and it is obvious, first, that the several joints between the parts may, by properly turning up or loosening their respective axial bolts *f*, be made fast or rigid or loose in operation to the degree required; second, that neither of the joints can make a complete rotation, because of the abutment of the pin *g*, connecting its outer lifts, *a* *b*, against the arm which connects a lift of said joint either to another of said joints next in order of arrangement or to one

of the tubular arms *D* *G*, as the case may be, and that as a consequence there can be no possibility of an entanglement and twist of 70 the electric wires about the exposed parts of the bracket; third, that the double jointing of the tubular arms *D* *G*, together with the joint of the arms to each other, such as herein described, obviously enables the bracket to be 75 brought to almost any position which may be desired, thus enabling, even if such a bracket is used alone with telephonic instruments, such instruments to be most easily and readily located for convenient use by operators. Of course, with mechanism such as shown as connecting the rod-standard *O* to the telephonic instruments, and which, as before stated, is embraced in another application for Letters Patent of the United States, filed March 26, 85 1883, it is plain the scope and variety of adjustment as to position for the telephonic instruments will, with the adjustments from brackets herein shown and described, be greatly increased and augmented.

p p are eyes or loops fastened to parts of the bracket herein described, for guides to the passage of the electric wire through the parts of the bracket, as has been herein described.

The tubular arms may be connected to each other by a double joint, as has been described for the connection of the other ends of each of said arms; and, again, the connection of said arms to the wall-plate *A* and to the rod-standard *O*, either or both, may be by a single joint—such as the joint *F*, described for connecting the two arms *D* *G* together—in lieu of a double joint, and yet secure in substance the objects of this invention; but it is preferable to joint the parts as has been particularly described, as by such jointing the greatest variety of adjustments is obtainable.

In Fig. 4 (being a view of the joint of the bracket detached) an outer lift of said joint is shown as provided with an arm, *j*, having thumb-screw *k* in position to be set against and loosened from the edge of the middle lift of said joint, and thereby enabling said joint to be fixed against and released to movement, which, as is obvious, in some cases might be advantageous to use.

An arm and thumb-screw, as above described, may be also applied to any one or more of the other joints of the bracket, or of the joints of the arms connecting the telephonic instruments to said bracket, and the application of said arm and thumb-screw is to be in such relation to the movement of the joint as not to interfere in the smallest degree 125 possible with the movement of the joint.

Having thus described my invention, what I claim, and desire to secure by Letters Patent, is—

1. A bracket for carrying telephonic and other instruments, composed of arms *D* and *G*, jointed together, and one jointed to a plate, *A*, and the other to a standard, *O*, in combination with instruments—such as a receiver,

K, and a transmitter, L—carried at opposite ends of said standard O, substantially as described, for the purpose specified.

2. A bracket for carrying telephonic and other instruments, composed of arms V V, constructed to be lengthened and shortened, and jointed to a common standard, O, which is jointed to an arm, G, in turn jointed to an arm, D, jointed to a plate or support, A, in combination with instruments—such as a receiver, K, and a transmitter, L—carried by said standard O, substantially as described, for the purpose specified.

3. A bracket for carrying telephonic and other instruments, composed of tubular arms D and G, jointed together, and the one, D, jointed to a plate, A, and the other to a rod standard, O, in combination with the guide-eyes p, attached to the parts of the bracket, substantially as described, for the purposes specified.

4. A bracket for carrying telephonic and other instruments, composed of arms D and G, jointed together by a joint in lifts a, b, and c, and the arm D, doubly jointed by joints M and M², each made of lifts a b c, to the plate A,

and the other arm, G, doubly jointed by joints N and N², each made of lifts a, b, and c, to rod-standard O, to which the telephonic or other instruments are connected, substantially as described, for the purpose specified. 30

5. The combination, with a joint in lifts a b c, connected by an axial pin and otherwise for the two outer lifts to turn as one and independently of the middle lift, and for said middle lift to turn upon said pin independently 35 of the outer lifts, of an arm attached to one of the outer lifts, and carrying a thumb-screw or other stop in position to be adjusted from the exterior of the joint, and thereby brought to a bearing against the edge of middle lift, 40 b, substantially as described, for the purpose specified.

In testimony whereof I have hereunto set my hand in the presence of two subscribing witnesses.

JAMES TREGURTHA.
